NEEDLE-THREADER

Daniel H. Chason, Elizabeth, N. J., assignor to
The Singer Manufacturing Company, Eliza-
beth, N. J., a corporation of New Jersey

Application July 30, 1936, Serial No. 93,360

3 Claims. (Cl. 223—99)

This invention relates to needle-threaders and it has as its primary object to provide a device of this nature which is extremely simple in construction and which therefore may be manufactured at a minimum of expense; which will be universal in its action, i. e., may be used to thread needles of substantially all commercial sizes and regardless of whether the needles are required to be threaded from left to right or from right to left; and finally one which may be readily used for threading either sewing machine needles or hand sewing needles.

As heretofore constructed, the simpler forms of needle-threaders have been capable of use only with a relatively small range of needle sizes and for only one type of threading, that is either from right to left or from left to right. It has, therefore, been the practice to provide four different threaders, one each for relatively large and small needles and one each for right and left threading.

Some of the more complicated and more expensive needle-threaders heretofore provided have been capable of universal action but the cost of such devices has greatly restricted their sale and use.

The needle-threader provided by this invention is extremely simple in construction, comprising only five parts, two of which are of sheet-metal and may be made by simple stamping operations, one consisting of an inexpensive wire threading hook, and the other two parts being a small rivet and a screw for securing the threading hook to the main shank. Due to the simplicity of design and the low cost of manufacture, the present device, which is universal in its action and which therefore is capable of doing the work of the more complicated and more expensive threaders, or four of the simpler forms of threaders, may be sold at a price comparable to the cheaper threaders heretofore available.

With the above and other objects in view, as will hereinafter appear, the invention comprises the devices, combinations and arrangements of parts hereinafter set forth and illustrated in the accompanying drawing of a preferred embodiment of the invention, from which the several features of the invention and the advantages attained thereby will be readily understood by those skilled in the art.

In the accompanying drawing, Fig. 1 is a side elevation of the improved needle-threader, illustrating its action in threading a sewing machine needle. Fig. 2 is a similar view showing it being used to thread a hand sewing needle. Fig. 3 is

a plan view of the device, as shown in Fig. 1. Fig. 4 is an enlarged left end view of the threader as shown in Fig. 1 and Fig. 5 is a view of the sheet-metal blank which constitutes the major element of the threader.

Referring more specifically to the drawing, the invention is disclosed as embodied in a needle-threader comprising a sheet-metal supporting shank or body member 1 which carries the threading elements later to be described, and which also serves as a hand grasp whereby the device may be held and manipulated. This element may be punched from flat stock and initially includes a forwardly extending tongue 2 and a laterally projecting tab 3. The member 1 also includes a head portion 4 which, as indicated at 5, is offset to one side of the body member approximately one-half the thickness of the latter. A rivet hole 6 and a screw hole 7, the latter of which is subsequently threaded for the reception of a screw, are also punched in the member 1 and a finger 8 is punched therefrom and pressed to one side thereof as shown most clearly in Fig. 4.

The head portion 4 is formed at its rear end with a retaining notch 9 into which fits the closed end 10^a of a bowed spring-metal needle-locating member 10 which is of flattened U-shape. The legs 10^b of the member 10 are located at the opposite sides of the head 4 and secured thereto by a rivet 11 which passes through the hole 6.

The legs 10^b project beyond the front end of the head 4 and have their outer ends flared outwardly at 10^c to form, between them, a substantially U-shaped needle-blade receiving mouth 12. This mouth merges into a throat 13 into which the needle moves as the device is used.

Secured to one side of the body member 1, by screw 14 threaded into the aperture 7, is a threader-hook 15. This hook is made of music wire and is preferably constructed as shown and described in my copending application Serial No. 12,354, filed March 22, 1935.

Intermediate its ends the shank of the threader-hook is located behind the finger 8 which supports and limits the movement of the hook.

Due to the offset arrangement of the head 4, which supports the needle-locating member 10, the threader-hook is located in line with the center of the needle-receiving mouth and therefore readily enters the needle-eye.

In the course of manufacture of the device the tab 3 is folded upwardly, along the line indicated by x in Fig. 5 thereby causing the projecting end of the tab to lie alongside the tongue 2. The forward ends of those elements are then

spread apart, as shown most clearly in Figs. 3 and 4 thereby forming between them a substantially U-shaped mouth which receives the point of a sewing machine needle and guards it against 5 contact with the thread during the threading operation. The lower forward edges of the tab and tongue are rounded and thereby facilitate in the drawing of the thread into the threadder-hook.

10 As previously stated, the present improved needle-threadder may be used with equal facility in threading either sewing machine needles *n*, as shown in Fig. 1 or hand sewing needles *h*, as shown in Fig. 2.

15 Having thus set forth the nature of the invention, what I claim herein is:—

1. A needle-threadder comprising a sheet-metal supporting shank provided with a laterally offset head portion formed, at its rear end, with a retaining notch; a bowed spring-metal member having a closed end fitted into said retaining notch and leg portions arranged at opposite sides of said offset head portion and projecting beyond the forward end thereof, the free ends of said 20 leg portions being flared outwardly in opposite directions to form between them a needle-receiving mouth the center of which is located at one side of the center line of said shank; means for securing said head and member together; and a 25 threading hook secured to one side of said shank in line with the center of said needle-receiving mouth.

2. A needle-threadder comprising a sheet-metal supporting shank provided with a laterally offset 30 head portion formed, at its rear end, with a retaining notch; a flattened U-shape spring-metal member having its closed end fitted into said retaining notch and its leg portions arranged at opposite sides of said offset head portion and projecting beyond the forward end thereof, the free 35

ends of said leg portions being flared outwardly in opposite directions to form between them a needle-receiving mouth the center of which is located at one side of the center line of said shank; a rivet passing through said head portion and said member, intermediate the ends of the latter, for securing them together; a threading hook secured to one side of said shank in line with the center of said needle-receiving mouth; and means on said shank engaging said hook to 10 limit the movement thereof.

3. A needle-threadder comprising a sheet-metal body member provided, adjacent one edge, with a laterally offset head portion formed, at its rear end, with a retaining notch, said body member also being provided adjacent its other edge with a forwardly projecting tongue and a laterally projecting tab, said tab being folded against said body member and the forward ends of said tongue and tab being flared outwardly in opposite directions to form a substantially V-shaped needle-point receiving mouth; a needle locating element comprising a bowed spring-metal member having its closed end fitted into said retaining notch and its leg portions arranged at opposite sides of said offset head portion and projecting beyond the forward end thereof, the free ends of said leg portions being flared outwardly in opposite directions to form between them a mouth adapted to receive the blade of the needle, the center of said mouth being located at one side of the center line of said body member; means for securing said body member and needle locating element together; a threading hook secured to one side of said body member in line with the center of said needle-receiving throat; and a finger pressed outwardly from said body member and engaging said hook to limit the movement thereof.
